UNITED STATES PATENT OFFICE

2,490,882

THREADING DEVICE

Clarence A. Pinkham, Douglaston, and Bartholomew Holohan, Kew Gardens, N. Y., assignors to Nelpin Manufacturing Co. Inc., Long Island City, N. Y., a corporation of New York

Application December 9, 1947, Serial No. 790,578

11 Claims. (Cl. 223—99)

1

This invention relates to threading appliances and more particularly to an improved, completely automatic threading appliance which threads the eye of a needle or similar device automatically upon insertion of the needle into a passage.

Various arrangements of needle threaders have been proposed, but all are relatively complicated to manipulate. Generally, it is necessary to hold the needle with its eye aligned with a threading hook, manually manipulate a hook operator to project it through the needle eye, lay the thread in the hook, and then withdraw the hook through the eye. While springs are sometimes used to make one or more of the operators self-executing, considerable manipulation is still required. Furthermore, such semi-automatic threaders are complicated in construction and liable to derangement in operation.

With the present appliance, it is necessary only to press the eye end of the needle into a receiving passage, lay the thread into a wide-mouthed slot, and thread the needle as it is being withdrawn. The appliance comprises only a few, simply assembled parts so arranged and interrelated as to function in a simple, non-complicated manner, and not easily subject to derangement.

More specifically, the present threading appliance comprises a base, having means for mounting a spool of thread, and a casing member secured to the base. The casing member comprises a pair of surface juxtaposed plates, one of which is molded, machined or the like to provide certain passages and recesses and the other of which acts as a closure or cover for such recesses and passages. Desirably, the base and casing may be made of a suitable translucent composition material, or non-translucent material may be used. Alternatively, the base and casing can be metal, wood, or any suitable material.

The casing member is formed with a needle receiving passage and a thread receiving slot intersecting the axis of the passage. A thread engaging element, such as a fine wire or flat metal hook, is pivotally mounted in a casing recess for movement across the axis of the passage and into the slot and thread engaging position therein. A biasing means, such as a spring, is provided normally to bias the hook toward the thread slot. Such movement is blocked, however, by a cam means, such as a plunger or anvil, mounted for longitudinal movement in a second passage aligned with the needle passage. Spring biasing means urge the cam means to a position blocking the intersection of the thread slot and the

2

needle passage and preventing movement of the hook into the thread slot.

The cam means spring is of greater strength than the hook biasing spring, so that the latter is effective to bias the hook into the slot only when the cam means is forced out of its hook obstructing position. The cam means is preferably an anvil or plunger having a cam surface on its upper end on which the hook rides in the inactive position, and a hook slot to guide the hook through the needle eye. Also, a needle aligning recess is formed on the upper end of the cam means in alignment with the hook slot.

To operate the appliance, the needle is inserted, 15 up end first, into the needle passage until it engages the needle recess in the anvil and moves the latter to the retracted position. A pair of flat, engaging leaf springs are disposed along the needle passage and are engaged by the needle eye to rotate the needle to align the eye with the hook. These springs exert sufficient frictional force against the needle to hold it from being ejected from the needle passage by the anvil spring acting to restore the anvil to its hook blocking position.

As the anvil is retracted, the hook is moved, 20 by its biasing spring, through the anvil hook slot and the needle eye into the thread slot. The thread is then drawn from a spool and laid in the thread slot, where it is held in place by a suitable friction clip lying alongside the thread slot.

When the needle is withdrawn, it is aided in 25 its outward passage by movement of the cam means under the action of its biasing spring, into its hook obstructing position. The eye of the needle as the latter is being withdrawn and urged outwardly as aforesaid, initiating the camming of the hook back toward its retracted position, and the hook pulls a thread loop through the eye.

As the cam means moves outwardly, the cam surface engages and cams the hook further into its retracted position. The needle is withdrawn from its passage, while the hook is still engaged with the thread loop, and in its movement pulls the loose end of the thread through the then fixedly positioned hook, leaving a single thread, rather than a loop, extending through the eye.

It is therefore among the objects of this invention to provide a simple, inexpensive threading appliance.

Another object is to provide such an appliance which operates automatically to thread a needle upon insertion of the needle into the appliance. A further object is to provide a threading ap-

pliance including cooperating mechanism operable by an inserted needle to thread the needle.

These and other objects, advantages and novel features of the invention will be apparent from the following description and the accompanying drawing. In the drawing:

Fig. 1 is a front elevation view of a needle threading device embodying the invention showing the elements in one position.

Fig. 2 is a vertical sectional view on the line 2—2 of Fig. 1.

Fig. 3 is a transverse sectional view on the line 3—3 of Fig. 1.

Fig. 4 is an elevation view, partly in section, on the line 4—4 of Fig. 3 and showing the elements of the device in an intermediate position.

Fig. 5 is a transverse sectional view on the line 5—5 of Fig. 1.

Fig. 6 is a partial elevation view showing the finish of a threading operation.

Fig. 7 is a plan view of the device.

Referring first to Fig. 7, the threading appliance comprises a base 10, preferably rectangular in form, on which is mounted a casing member 15 and a pin 11 for supporting a spool 12 containing thread 20. Casing member 15, which is perpendicular to base 10 and preferably located near an edge of the base at some distance from pin 11, contains the elements of the threading appliance. Base 10 and casing member 15 may be made of any suitable material, although a transparent composition material is preferred.

Casing member 15 comprises a pair of peripherally congruent plates 16, 17, secured together by suitable means such as rivets 18. Plate 16, which is thicker than plate 17, is formed with open faced recesses to receive the threading mechanism, and plate 17 acts as a closure for such recesses.

Plate 16 is formed with a needle receiving passage 25, comprising an upper section 21 having a flared opening 22, a lower section 23 having a flared opening 24 and an open, relatively large intermediate recess 26 closed by plate 17. Lower section 23 opens into a large, inverted L-shaped open recess 27 in plate 16, closed by plate 17, which recess houses certain elements of the threading appliance.

A thread receiving slot 30 extends diagonally inward and then downward from one side of casing member 15 into recess 27 and its axis of passage 25. Also in recess 27 is a mounting member 31 having a nose 32 and an oppositely directed heel 33. Member 31 is pivotal on a pin 34 and is biased to swing in a counter clockwise direction by a tension spring 36 connected between heel 33 and a pin 37. Such counter clockwise bias tends to urge a threading device, such as a wire hook 35 secured to nose 32, across the axis of needle passage 25 and into thread slot 30 to engage a thread 20 therein.

Such movement of hook 35 is normally blocked by a plunger or anvil 40 which is movably mounted in a recess 41 aligned with needle passage 25. The shank 42 of anvil 40, and recess 41 are rectangular in cross-section to prevent rotational movement of the anvil. A compression spring 43 normally biases the cam head 45 of anvil 40 to a position blocking movement of hook 35 into slot 30. For this purpose, spring 43 is made to have greater strength than spring 36.

Cam head 45, as best seen in Figs. 2 and 4, is formed with a longitudinal slot 46 for receiving the eye end of a needle 50 and a deep narrow

transverse slot 47, intersecting slot 46 at right angles, for receiving and guiding hook 35. A cam ear 48 extends laterally from anvil 40 toward member 31, and has a sloping cam surface 49. Surface 49 intersects head 45 at the base of transverse hook slot 47. Normally, hook 35 rides on cam surface 49, in the retracted position, and as anvil 40 is depressed by a needle 50, rides into slot 47. As the needle is withdrawn and anvil 40 moves upwardly, cam surface 49 swings hook 35 and member 31 clockwise to the retracted position.

In order for the appliance to operate to thread a needle, it is necessary for the eye 51 of a needle 50 to be axially aligned with hook 35. It is well-known that a needle is flattened adjacent its eye, with the flat surfaces extending perpendicular to the axis of the eye. Accordingly, a pair of flat springs 52 are mounted in passages 53 diverging upwardly from recess 26. The lower ends of springs 52 are bowed or curved, and are in substantial abutment on the axis of passage 25. As the eye end of a needle 50 is inserted into passage 25, springs 52 are engaged by the needle eye and effect rotation of the needle until the flat needle surfaces adjacent the eye are engaged by the flat surfaces of springs 52. This aligns the needle eye with hook 35. Additionally, springs 52 exert sufficient pressure against the needle to hold anvil 40 retracted against the force of its spring 43.

As stated, the appliance operates automatically in response to pressing of a needle 50, eye end first, into passage 25. As the needle is pressed in, springs 52 cause the needle to rotate to align the eye 51 with hook 35.

Further downward movement of needle 50 engages its eye end in slot 46 of cam head 45, and pressure on the needle moves anvil 40 downward, compressing spring 43. Spring 36 swings member 31 counter clockwise as hook 35 rides along cam slot 47. As needle 50 and anvil 40 continue their downward movement, eye 51 is aligned with hook 35 and the latter passes through eye 51 and into slot 30 in thread engaging position as shown in Fig. 4. The thread 20 is then drawn from its spool and the free end thereof is laid in slot 30, being drawn towards the closed end of such slot. To hold thread 20 in slot 30, a spring clip 60 is secured alongside the slot, with its arms sprung inwardly of the slot into abutment. Thread 20 may be easily drawn between the clip arms.

When the upward movement of the needle 50 is initiated by manual action against the pressure of springs 52, spring 43 forces anvil 40 and needle 50 upwardly. As the upward movement of the needle 50 is continued by further manual action and the expansion of spring 43 against anvil 40, the rearmost inner surface of needle eye 51 cams hook 35 clockwise until hook end 38 rides out of the eye, and into hook slot 47, drawing a loop of thread 20 through the eye, as seen in Fig. 6. As anvil 40 continues to move upwardly, hook 35 rides out of slot 47 and is cammed to its retracted position, shown in Fig. 1 by cam surface 49 of ear 48. As needle 50 in its upward movement is entirely withdrawn from passage 25, it pulls a double thread loop up into passage 25, the free end of the thread being drawn around and eventually clears hook 35, leaving the needle threaded with a single strand of thread 20. Thread 20 from the spool may then

be pulled through passage 25 in the desired amount and severed.

It will thus be seen that a novel threading appliance has been provided which is operated automatically solely by pressing the eye end of a needle into a needle passage. A spring biased, thread engaging hook is normally blocked from entering a thread receiving slot by a hook camming anvil which is biased by a stronger spring to a blocking position. When the anvil is moved to its retracted position by pressure of the needle, the hook biasing spring swings the hook through the needle eye to catch a thread. Upon withdrawing the needle, the needle eye and the anvil conjointly cam the thread hook to its retracted position to draw a thread loop through the needle eye. Flat springs in the needle passage automatically align the needle eye with the thread hook.

Additionally, the appliance comprises only a very few simple and rugged parts. Derangement is substantially impossible, and the operation of threading is extremely simple. All that is necessary is to lay a thread in slot 30 and press a needle, eye end first, into passage 25. When the pressure on the needle is released, the needle is forced outwardly, threaded.

While a specific embodiment of the invention has been shown and described in detail to illustrate the principles of the invention, it will be understood that the invention may be otherwise embodied without departing from such principles.

What is claimed is:

1. A threading appliance comprising, in combination, a member formed with a passage to receive a device having an eye to be threaded and a thread receiving slot intersecting the axis of such passage; a thread engaging element movable across the axis of such passage and into the slot to engage a thread disposable therein; means biasing said element toward the slot; and cam means normally obstructing such movement of said element; said cam means being displaceable by the device inserted in the passage, to release said element for movement by said biasing means through the eye of the device and into the slot and thread engaging position; said cam means, upon withdrawal of the device, forcing said element to its retracted position and said element, in retracting, drawing a loop of the thread through the eye of such device to thread the latter.

2. A threading appliance comprising, in combination, a member formed with a passage to receive a device having an eye to be threaded and a thread receiving slot intersecting the axis of such passage; a thread engaging element movable across the axis of such passage and into the slot to engage a thread disposable therein; first means biasing said element toward the slot; cam means engageable by a device inserted in the passage; and second means biasing said cam means to a position obstructing movement of said element into the slot; said cam means being displaceable by the device inserted in the passage, to release said element for movement by said first means through the eye of the device and into the slot and thread engaging position; said second means, upon withdrawal of such device, moving said cam means toward its obstructing position to force said device to its retracted position and said element, in retracting, drawing a loop of the thread through the eye of such device to thread the latter.

3. A threading appliance comprising, in com-

bination, a member formed with a passage to receive a device having an eye to be threaded and a thread receiving slot intersecting the axis of such passage; a thread engaging element movable across the axis of such passage and into the slot to engage a thread disposable therein; first means biasing said element toward the slot; cam means engageable by a device inserted in the passage; and second means biasing said cam means to a position obstructing movement of said element into the slot; said cam means being displaceable by the device inserted in the passage, to release said element for movement by said first means through the eye of the device and into the slot and thread engaging position; said second means, upon withdrawal of such device, moving said cam means toward its obstructing position to force said device to its retracted position and said element, in retracting, drawing a loop of the thread through the eye of such device to thread the latter; the biasing effect of said second means being stronger than that of said first means.

4. A threading appliance comprising, in combination, a member formed with a passage to receive a device having an eye to be threaded and a thread receiving slot intersecting the axis of such passage; a thread engaging element movable across the axis of such passage and into the slot to engage a thread disposable therein; means in the passage effective to engage the inserted device to align the eye with said element; means biasing said element toward the slot; and cam means normally obstructing such movement of said element; said cam means being displaceable by the device inserted in the passage, to release said element for movement by said biasing means through the eye of the device and into the slot and thread engaging position; said cam means, upon withdrawal of the device, forcing said element to its retracted position and said element, in retracting, drawing a loop of the thread through such device to thread the latter.

5. A threading appliance comprising, in combination, a member formed with a passage to receive a device having an eye to be threaded and a thread receiving slot intersecting the axis of such passage; a thread engaging element pivotally mounted in said member for swinging movement across the axis of such passage and into the slot to engage a thread disposable therein; spring means normally biasing said element to swing toward the slot; and cam means normally obstructing such movement of said element; said cam means being displaceable by the device inserted in the passage, to release said element for movement by said spring means through the eye of the device and into the slot and thread engaging position; said cam means, upon withdrawal of the device, swinging said element to its retracted position and said element, in retracting, drawing a loop of the thread through the eye of such device to thread the latter.

6. A threading appliance comprising, in combination, a member formed with a passage to receive a device having an eye to be threaded and a thread receiving slot intersecting the axis of such passage; a thread engaging element pivotally mounted in said member for swinging movement across the axis of such passage and into the slot to engage a thread disposable therein; first spring means normally biasing said element to swing toward the slot; cam means longitudinally movable in alignment with the passage and en-

gaging said element; and second spring means biasing said cam means to a position holding said element retracted from the passage; said second spring means being compressed by a device inserted in the passage and engaging said cam means to provide for said first spring means to swing said element through the eye of the device into the slot and thread engaging position; said second spring means, upon withdrawal of the device, forcing said cam means to swing said element to such retracted position and said element, in retracting, drawing a loop of the thread through the eye of such device to thread the latter.

7. A threading appliance comprising, in combination, a member formed with a passage to receive a needle having an eye to be threaded and a thread receiving slot intersecting the axis of such passage; a thread engaging element pivotally mounted in said member for swinging movement across the axis of such passage and into the slot to engage a thread disposable therein; means in the passage effective to engage the inserted needle to align the eye with said element; first spring means normally biasing said element to swing toward the slot; cam means longitudinally movable in alignment with the passage and engaging said element; and second spring means biasing said cam means to a position holding said element retracted from the passage; said second spring means being stronger than said first spring means; said second spring means being compressed by a needle inserted in the passage and engaging said cam means to provide for said first spring means to swing said element through the eye of the needle into the slot and thread engaging position; said second spring means, upon withdrawal of the needle, forcing said cam means to swing said element to such retracted position and said element, in retracting, drawing a loop of the thread through the eye of such needle to thread the latter.

8. A threading appliance comprising, in combination, a member formed with a passage to receive a needle having an eye to be threaded and a thread receiving slot intersecting the axis of such passage; a thread engaging element pivotally mounted in said member for swinging movement across the axis of the passage and into the slot to engage a thread disposable therein; flat spring means extending along the passage to engage a needle and align its eye with said element; first spring means normally biasing said element to swing toward the slot; cam means longitudinally movable in alignment with the passage and engaging said element; and second spring means biasing said cam means to a position holding said element retracted from the passage; said second spring means being stronger than said first spring means; said second spring means being compressed by a needle inserted in the passage and engaging said cam means to provide for said first spring means to swing said element through the eye of the needle into the slot and thread engaging position; said second spring means, upon withdrawal of the needle, forcing said cam means to swing said element to such retracted position and said element, in retracting, drawing a loop of the thread through the eye of such needle to thread the latter.

9. A threading appliance comprising, in combination, a member formed with a first, relatively small diameter passage to receive a needle, a second larger diameter passage aligned with said first passage and a thread receiving slot intersect-

ing the upper portion of such second passage; a thread engaging element pivotally mounted in said member for swinging movement across the second passage and into the slot to engage a thread disposable therein; first spring means normally biasing said element to swing toward the slot; a plunger slidably mounted in the second passage and having a cam surface on its outer end engaging said element; second spring means biasing said plunger outwardly so that said cam surface forces said element to a retracted position; said second spring means being stronger than said first spring means; said second spring means being compressible by a needle inserted in the first passage and engaging the plunger outer end whereby the cam surface is retracted to provide for said first spring means to swing said element through the needle eye into the slot and thread engaging position; the needle eye, upon release of the needle, camming said element toward the retracted position and said cam surface then engaging said element to continue camming the same toward the retracted position, and said element, in retracting, drawing a loop of the thread through the eye of such needle to thread the latter.

10. A threading appliance comprising, in combination, a member formed with a first, relatively small diameter passage to receive a needle, a second larger diameter passage aligned with said first passage and a thread receiving slot intersecting the upper portion of such second passage; a thread engaging element pivotally mounted in said member for swinging movement across the second passage and into the slot to engage a thread disposable therein; means effective to engage the inserted needle to align the eye with said element; first spring means normally biasing said element to swing toward the slot; a plunger slidably mounted in said second passage and having a cam surface on its outer end engaging said element; second spring means biasing said plunger outwardly so that said cam surface forces said element to a retracted position and said plunger, in the outer position, closing the inner end of the slot; said second spring means being stronger than said first spring means; said second spring means being compressible by a needle inserted in the first passage and engaging the plunger outer end whereby the cam surface is retracted to provide for said first spring means to swing said element through the needle eye into the slot and thread engaging position; the needle eye, upon withdrawal of the needle, camming said element toward the retracted position and said cam surface then engaging said element to continue camming the same toward the retracted position, and said element in retracting, drawing a loop of the thread through the eye of such needle to thread the latter.

11. A threading appliance comprising, in combination, a member formed with a first, relatively small diameter passage to receive a needle, a second larger diameter passage aligned with said first passage, and a thread receiving slot intersecting the upper portion of such second passage; an element pivotally mounted in said member; a thread engaging hook mounted on said element and extending toward the intersection of the second passage and the slot; flat spring means extending along the first passage to engage a needle and align its eye with said hook; first spring means normally biasing said element to swing the hook toward the slot and into thread engaging position; a plunger slidably

mounted in the second passage and having a cam surface on its outer end engaging said hook; second spring means biasing said plunger outwardly so that said cam surface forces said hook and element to a retracted position; said plunger, in the outer position, closing the inner end of the slot; the needle eye, upon withdrawal of the needle, camming said hook toward the retracted position and said cam surface then engaging said hook to continue camming the 10 same toward the retracted position, and said hook, in retracting, drawing a loop of the thread through the eye of such needle to thread the latter.
